ATTORNEY

UNITED STATES PATENT OFFICE.

VICTOR DEINERT, OF EMERALD, NEBRASKA.

SPARK-ARRESTER.

1,286,553.

Specification of Letters Patent.

Patented Dec. 3, 1918.

Application filed May 4, 1917. Serial No. 166,447.

To all whom it may concern:

Be it known that I, VICTOR DEINERT, a citizen of the United States, residing at Emerald, in the county of Lancaster and 5 State of Nebraska, have invented new and useful Improvements in Spark-Arresters, of which the following is a specification.

This invention relates to spark arresters designed for use in connection with the 10 smoke box of locomotive boilers, and embodies among other features a longitudinally disposed partition dividing the smoke box into separate compartments, and serving to confine the products of combustion in the 15 lowermost compartment an appreciable length of time, with a view of destroying the sparks in this compartment, and thus preventing the passing of the same into the atmosphere through the other compartment 20 and smoke stack, which quite frequently causes damage to adjacent buildings by fire.

In carrying out my invention I provide means whereby the partition is firmly supported within the smoke stack, but susceptible of being removed therefrom to be cleaned, or for any other purpose as the 25 occasion may require.

The nature and advantages of the invention will be better understood when the following detail description is read in connection with the accompanying drawing, the invention residing in the construction, combination and arrangement of parts as 30 claimed.

35 In the drawing forming part of this specification and wherein like numerals of reference indicate similar parts in the several views:—

Figure 1 is a horizontal sectional view 40 through the smoke box of a locomotive showing the invention.

Fig. 2 is a vertical longitudinal sectional view therethrough.

Fig. 3 is a vertical transverse sectional 45 view, taken on line 3—3 of Fig. 2.

Referring more particularly to the drawing 10 indicates the smoke box of a locomotive boiler, which may be of any preferred construction, provided with the usual

smoke stack 11 and door 12. Arranged with- 50 in the smoke box at diametrically opposite points are spaced longitudinally extending cleats 13, each pair of the latter defining guides for the horizontally disposed partition 14. The latter is coextensive in length 55 with the length of the smoke box and is provided with a plurality of apertures 15, the apertures disposed in the vicinity of that part of the partition under the smoke stack, where the strongest draft occurs, be- 60 ing much smaller than the remaining apertures. If desired the partition may be also provided with a nozzle 16 which is disposed immediately beneath and in a line with the smoke stack 11, the nozzle having a re- 65 stricted bore and outlet. The partition is disposed slightly above the fire tubes 17, and it is manifest that the products of combustion are introduced into the smoke box be- 70 neath the partition 14, which latter confines 75 the smoke and other products of combustion within the space beneath the partition an appreciable length of time, with a view of destroying the sparks, and thus preventing the latter from escaping from the smoke box 75 through the stack 11 to the atmosphere. Extending transversely of the smoke box are 80 bars 18 having their upper surfaces lying flush with the corresponding surfaces of the lowermost cleats 13, so that the partition 14 will rest upon the bars and be thereby firmly supported within the smoke box. However the construction and arrangement is such that the partition 14 can be readily and easily withdrawn from the smoke box 85 through the forward end thereof, subsequent to the opening of the door 12, when it is desired to clean the partition, to replace the same by a new one, or for any other purpose as the occasion may require. 90

While it is believed that from the foregoing description the nature and advantages of the invention will be readily apparent, I desire to have it understood that such changes may be resorted to when desired as 95 fall within the scope of what is claimed.

What is claimed is:—

In combination with the smoke box of a

locomotive boiler having a stack, a spark arrester comprising a horizontally disposed partition plate slidably arranged within the smoke box and extending entirely across substantially the central portion thereof, said plate being provided with a plurality of holes, the group of holes immediately be-

neath the stack being of considerably less diameter than the remaining holes whereby the draft at its area of maximum strength 10 will be materially retarded.

In testimony whereof I affix my signature.

VICTOR DEINERT.
